United States Patent Office.

E. A. DAYTON, OF RICHMOND, VIRGINIA.

Letters Patent No. 89,637, dated May 4, 1869.

IMPROVEMENT IN BEARINGS FOR VERTICAL SHAFTS.

The Schedule referred to in these Letters Patent and making part of the same.

To all whom it may concern:

Be it known that I, E. A. DAYTON, of Richmond, in the county of Henrico, and State of Virginia, have invented a new and useful Improvement in Bearings for Vertical Shafts; and I do hereby declare that the following is a full, clear, and exact description thereof, which will enable others skilled in the art to make and use the same, reference being had to the accompanying drawings, forming part of this specification.

This invention relates to improvements in bearings for vertical shafts, designed to be applied either as steps for the ends of the shafts, or intermediate bearings, which said bearings are especially adapted to facilitate the lubrication of the shafts, as hereinafter more fully specified.

Figure 1 represents a plan view of my improved bearing.

Figure 2 is a horizontal section, taken on the line *y y* of fig. 3.

Figure 3 represents an elevation, partly in section,

Figures 4 and 5 represent a modification of the method of tightening and adjusting the wearing-surfaces.

Similar letters of reference indicate corresponding parts.

A represents the body of the box, which may be provided with lugs *B*, for securing to the framing, or it may, in a modified form, be secured thereto by letting into the frame or bridge-tree, as represented in fig. 4.

The said part *A* has a central hole through it vertically, larger than the diameter of the shaft as seen in fig. 2, at *C*, and a tubular extension *D*, rising from the bottom, around the said hole, forming, between it and the outer shell, a space for the oil and the adjustable journal *E* of the shaft, which consists of a cylindrical piece, fitted to the shaft and hollowed from the bottom sufficiently to provide space for the tubular projection *D* of the box.

The bearing-surfaces are segmental pieces *F*, fitted to the exterior of the journal *E*, and placed in the space of the box, between the shell and the part *D*, and adjusted against the journal *E* by the set-screws *G*, tapped through the shell of the box.

The said space may be filled with oil, which will have free application to the bearing-parts, and constantly lubricate them without waste.

Holes may be made in the top and bottom of the box for the introduction and removal of the oil, and plugged or otherwise stopped, as may be desired.

According to another plan of arrangement for tightening the box, to compensate for wear, a second tubular extension, *H*, from the bottom, may be provided, of larger internal diameter at the top than at the bottom, and the journal-bearings *E* may be tapered to fit the same, and may be adjusted on the shaft in a downward direction, to take up any looseness occasioned by wear.

Holes *I* may be made through the bottom of the part *H*, to allow the oil to communicate with the bearing-surfaces.

If it be desired to employ this improved bearing for strips, the lower end of the journal-bearing *E* may rest and turn on the bottom of the box *A*.

Having thus described my invention,
I claim as new, and desire to secure by Letters Patent—

1. The box *A*, journal-bearing *E*, segmental bearings *F*, and shaft, all combined and arranged substantially as and for the purpose specified.

2. The box *A*, provided with the fixed bearing *H* and vertical tubular extension *D*, the tapered adjustable journal-bearing *E*, and shaft, all combined and arranged substantially as and for the purpose specified.

E. A. DAYTON.
